ICE HEADING MACHINE

Milton T. Maddox, Fort Worth, Tex.

Application July 5, 1945, Serial No. 603,385

6 Claims. (Cl. 214—1)

1

This invention relates to handling devices and it has particular reference to apparatus for handling ice in what is conventionally referred to in the ice industry as "heading" ice cakes or blocks, that is, ending up the blocks as they are discharged from the freezing cans, and which operation is ordinarily done by hand. The principal object of the invention, therefore, resides in the provision of apparatus which, by its novel arrangement of parts, receives the ice blocks as the same are discharged from the freezing cans and automatically raises the said blocks to upright positions whereby manual handling, such as loading, storing, and the like, is expedited and thus time and labor is saved.

Another object of the invention resides in the provision of an ice handling device which is simply and economically constructed, although entirely automatic in operation, and which can be installed in any plant without special adaptations.

Yet another object of the invention is manifest in the provision of a combination of elements whereby many of the hazards attendant upon handling of heavy ice blocks, usually weighing 300 pounds each, are completely eliminated since by manual manipulation of the blocks many workmen have been injured, some seriously.

Broadly, the invention seeks to comprehend the provision of a device by which the ice industry, already seriously affected by automatic refrigeration, can maintain maximum production and efficiency and maximum profits by a saving in operating costs.

While the foregoing objects are paramount, other and lesser objects will become manifest as the description proceeds, taken in connection with the appended drawings wherein:

Figure 1 illustrates the invention in side elevation showing, in dotted lines, the various positions of the ice cans in heading the ice blocks, the latter being shown in upright position.

Figure 2 shows the invention in plan and illustrates two blocks of ice about to be raised, or "headed" and showing the automatic reversing mechanism for the ice cans.

Figure 3 fragmentarily illustrates in elevation one of the automatic locking devices for retaining the ice in the cans.

Figure 4 is a fragmentary plan view of one of the locking devices shown in Figure 3.

Figure 5 fragmentarily illustrates, in perspective, the switch for stopping the electric motor shown in Figures 1, 2 and 8.

Figure 6 is a fragmentary illustration, in plan,

of the starting switch for the motor and fragmentarily showing the cans in lateral cross-section.

Figure 7 is another fragmentary cross-sectional view of the cans illustrating the starting switch in elevation.

Figure 8 is a perspective illustration of the invention showing the normally inclined positions of the cans, which are rigidly connected, and illustrating the motor, the driving mechanism and one of the raising chains.

Figure 9 is a fragmentary perspective illustration of one of the actuating chains with lug attached.

15 The invention comprises, primarily, a frame structure 1, which is rectangular in plan, having its forward end open at the top as shown particularly in Figure 8. The side members 2 are tied across the bottom by a relatively thin plate 3 extending beyond the sides 2 to accommodate suitable braces 4 which rigidify the side members 2, in the manner illustrated in Figures 1, 2 and 8.

20 A pair of receptacles 5, which will be herein-after referred to as cans 5, are arranged within the frame 1 so that their open ends 6 are pivotally connected at 7 to the forward open end of the frame 1. Gussets 8 are integrally secured in the lower forward ends of the side members 2 of the frame 1, as shown in Figures 1 and 8, in which the pivots 7 are arranged. The cans are rigidly connected by brackets 9 therebetween, shown in Figures 2 and 8, and have stub shafts 10 rigidly projecting from the opposite sides of the associated cans 5 and journaled in the gussets 8 providing the pivots 7.

25 The cans 5 are thus reclining in the frame 1 connected thereto only by the pivots 7 and at their lowermost forward ends 6 so that they can be raised upon their forward ends through the open end of the frame 1, in the manner illustrated in dotted lines in Figure 1. Normally the cans 5 assume an inclined position in the frame 1, their closed ends 11 being rearwardly of the frame 1 and substantially higher than their forward ends 6, as illustrated in Figures 1 and 8. The rearmost ends of the cans 5 are supported upon a laterally disposed member 12 arranged through the frame 1 to which is attached cushioned elements, or bumpers 13, shown in Figures 1 and 8.

30 On opposite sides of the connected cans 5 are levers 14 rigidly attached to the cans 5 so that their greater longitudinal portions are spaced outwardly from the walls of the cans 5 and extend rearwardly thereof. The levers 14 function to provide for raising the cans 5 to upright positions

shown in dotted lines in Figure 1. This is accomplished by chains 15 operating on sprockets 16 and 17. Lugs 18 are rigidly coupled into the chains 15, illustrated in detail in Figure 9, which engage the levers 14 to raise the cans as the sprockets 16 are operated by the motor 19 through the gear arrangement 20 and 21.

The lugs 18, shown in detail in Figure 9, are preferably provided with rollers 22, or the like, and may be of any desirable form suitable for the purpose intended. The levers 14 are of sufficient length to permit the cans 5 to be completely raised to the vertical positions shown in dotted lines in Figure 1, the rollers 22 serving to minimize the frictional contact between the lugs 18 and the levers 14 as the cans are raised.

In operation, the invention is positioned directly in front of the chutes (not shown) from which the ice blocks 23 are delivered from the freezing cans. The open end of the frame 1 is directed towards the chutes so that the open ends 6 of the cans are in alignment with the ice chutes. In some installations it may be desirable to provide guides 24 for the ice blocks directing them into the cans 5 as they slide from the chutes. The blocks 23, usually weighing 300 pounds, will slide into the cans 5 through their open ends 6, and in so doing, cause the spring actuated latches 25, pivoted vertically on each side of each of the cans 5, to pivot inwardly as shown in dotted lines in Figure 4, and due to their spring action operate to trap the ice blocks 23 within the cans 5 so that the blocks can be raised upright and discharged in their perpendicular positions as illustrated in Figure 1.

As the ice blocks 23 pass into the cans 5 their opposite inner surfaces, that is, the surfaces nearest the connected walls of the cans 5, will engage and depress the springs 26, which are already in engagement with plungers 27 arranged through the walls of the cans 5, bringing together a pair of electrical contacts 28 which closes the circuit of the motor 19. The switch 28 is of the type which causes the closing of the electrical circuit by a solenoid, or the like, since a different switch 29 is provided for opening the motor circuit and which will presently be described. It is not intended, however, that the invention be limited to the particular types of switches shown and described since obviously any suitable switch arrangement may be employed.

As the cans 5 are raised, as illustrated in Figure 1, the limitation of the lifting function of the motor 19 is reached when the cans 5 assume the position A shown in dotted lines in Figure 1 since the lugs 18 are now passing over the uppermost sprocket 17. The weight of the ice blocks 23, however, will carry the cans 5 on beyond the center of gravity to the position B where the cans 5 are inclined slightly forward to cause the blocks 23 to slide out on their ends. The momentum gained in the sudden forward tilt of the cans 5 will cause the blocks 23 to slide clear of the cans 5.

In their movement forward from the position A to the position B, shown in Figure 1, the levers 14 engage hooks 30 which are positioned in their paths near the top and at the front of the frame 1. These hooks 30 are shown particularly in Figure 2 and each is connected to the ends of cables 31 arranged through apertures in gussets 32 of plates 33 suspended to the sides 2 of the frame 1. The cables 31 are passed over pulleys 34 and connected to weights 35. As the ice blocks 23, therefore, are discharged from the cans 5 the weights exert sufficient force thereon to urge

these members back past the center of gravity whereupon they fall back into their normal inclined positions, the bumpers 13 absorbing the shock of their fall. It is obvious, however, that 5 any suitable shock absorbing devices, such as springs, hydraulic apparatus, or the like, may be resorted to.

It will also be observed that the switch 29, previously referred to, is arranged on one side of the frame 1 at the forward end thereof. The switch 29 is of a conventional type and functions similarly to the switch 28 previously described. A lever 36 is arranged on the switch 29, as shown in Figures 2 and 5, which is spring actuated and extends into the path of one of the levers 14 as the same moves with the cans 5.

Similarly to the hooks 30 the lever 36 is engaged by the lever 14 as the cans 5 are moved forwardly by the weight of the ice blocks 23 and the switch 20 is operated to open the motor circuit to stop the motor 19. Thus the motor will operate only when ice blocks 23 are in the cans 5 resulting in a saving of electrical current as well as wear on the motor and the driving mechanism. The occurrence 25 of the discharge of the ice blocks from the freezing cans frequently varies and the invention need not be required to function except when the ice blocks are ready to be headed.

Manifestly certain changes and modifications 30 of the invention may be resorted to from time to time by persons skilled in the art without departing from the spirit and intent of the invention or the scope of the appended claims.

What is claimed is:

35 1. In an ice heading machine having a frame, a pair of rigidly connected normally reclining ice cans having pivotal connection forwardly of the said frame and adapted to be raised to a substantially vertical position therein, a motor and motor-driven means for raising the said cans, a switch for said motor engageable by ice cakes entering said cans to energize said motor, means comprising weighted cables for tilting the cans toward their normal reclining position when empty and an electric switch for automatically 40 stopping the said motor operated by the movement of the said cans.

2. In an ice heading machine having a frame, a pair of rigidly connected and normally reclining ice cans, the said cans being pivoted in the said frame towards the forward end thereof, an electric motor providing means for raising the said cans to a substantially vertical position to discharge the ice therefrom, a switch for said 50 motor in one of said cans actuated by ice cakes entering the same, means comprising weighted cables engageable with said cans for aiding in returning the same to their normal position by gravity after discharging the ice therefrom, and automatic means actuated by the movement of the said cans for stopping the said motor.

3. In an ice heading machine having a frame and paired ice cans pivotally arranged therein, the said cans being normally in an inclined position in the said frame and pivoted thereto forwardly thereof, a motor in said frame for raising the said cans to a substantially vertical position in the said frame, means comprising weights on cables engageable with said cans for tilting and returning the same toward their normal inclined positions, and automatic means, actuated by the movement of the said cans, stopping the said motor.

4. In an ice handling machine having a frame, 70 a pair of rigidly connected ice cans pivotally ar-

ranged in an inclined position in the said frame so that the said cans can be raised to a vertical position forwardly of the said frame, a motor and motor-driven means in the said frame operating chains on sprockets raising the said cans to the vertical position, means comprising a weight aiding in returning the said cans to their normal position, and switches actuated by said cans automatically stopping the said motor.

5. In an ice handling machine having a frame, a pair of rigidly connected ice cans normally reclining in the said frame and pivoted forwardly thereof, a motor and motor driven means raising the said cans on their said pivots to a vertical position, a switch for starting said motor actuated by ice cakes entering said cans, means in the said frame comprising weighted cables engageable with said cans whereby to urge the same toward their normal position therein, and automatic means comprising a switch actuated by said cans in their vertical positions for stopping the said motor.

6. In a machine for heading ice, a frame having a pair of ice cans pivotally arranged therein

and normally inclined forwardly of the said frame, a motor and motor driven chains operatively arranged in the said frame for raising the said cans on their pivots to a vertical position, a starting switch for said motor actuated by ice cakes entering said cans, weights operating on cables in the said frame to urge the said cans to past their pivotal center of gravity and toward their normal positions when empty, and a stopping switch actuated by said cans in their vertical positions for stopping the said motor.
